UNITED STATES PATENT OFFICE.

JAMES MILTON WAUGH, OF CHICAGO, ILLINOIS

TANK-CAR.

1,248,763.

Specification of Letters Patent.

Patented Dec. 4, 1917.

Application filed August 10, 1914. Serial No. 856,004.

To all whom it may concern:

Be it known that I, JAMES MILTON WAUGH, a citizen of the United States, and a resident of the city of Chicago, in the county of Cook and State of Illinois, have invented certain new and useful Improvements in Tank-Cars; and I do hereby declare that the following is a full, clear, and exact description of the same, reference being had to the accompanying drawings, and to the numerals of reference marked thereon, which form a part of this specification.

This invention relates to an improved form of rigging for supporting a tank or a car body upon a car underframe, so that impact imposed upon the car, as well as other causes, such as changes in speed which bring into effect the inertia of the tank and its contents, tending to permanently shift the tank on the frame or to break the same loose from the frame are entirely overcome. The invention also relates to a construction whereby the expansion and contraction of the tank and frame, due to temperature changes, is readily permitted. In the past great and apparently insurmountable difficulties have been encountered in all endeavors to construct tank cars wherein the enormous stresses imposed upon the tank, the under frame and the attaching means therebetween could be properly taken care of. Generally the result of such forces is the springing or warping of the tank or other damage thereto causing leakage. Heretofore in an endeavor to partly correct the defects of construction and mounting the tanks sometimes have been slidably mounted upon the car frame; but it has been found that the stresses occasioned in buffing and otherwise results in frequent and violent impact of the tank against the abutments provided to limit its movement relatively the frame, soon proving disastrous, even to the most powerful constructions. However, in the present invention I propose to mount a tank slidably upon a car underframe with shock absorbing mechanism provided at the ends and intermediate the tank, so that the inertia effect of the tank and its contents may be transmitted yieldingly to the car frame, thus preventing injury to the tank and to the supporting means therefor.

It is an object of this invention to construct a tank car wherein suitable shock absorbing devices are provided to take up the

impact stresses imposed upon the car framing by the tank, which is adjustably mounted upon the car framing.

It is also an object of this invention to construct an improved form of tank car in which the tank is slidably mounted on the frame and in which, in addition to the usual or any draft and buffing gear for the car, a specially constructed type of buffing or shock absorbing rigging is built on the car frame at the ends and intermediate the ends thereof to coact with suitable abutments on the tank, or vice versa, to take up the excessive impact stresses between the tank and the car frame.

It is also an object of this invention to construct a shock absorbing means so constructed as to be readily adaptable to the type of car frame now in general use, and acting with suitable guides to releasably support a tank to absorb impact stresses and also permit ready removal of the tank and the substitution of another when so desired.

It is furthermore an object of this invention to afford means for absorbing the stresses occasioned by the inertia of an inelastic load (the tank and contents) when the car frame is subjected to stresses, due to buffing or to draft.

It is finally an object of this invention to construct a tank car wherein the tank is yieldably supported upon the car frame and normally centralized thereon by means of a spring friction plate buffing rigging, which absorbs impact stresses imposed upon the tank or car framing, and transmitted from one to the other.

The invention (in a preferred form) is illustrated in the drawings and hereinafter more fully described.

In the drawings:

Figure 1 is a side elevation of a car embodying the principles of my invention.

Fig. 2 is a top plan view thereof with the tank omitted.

Fig. 3 is a bottom plan view of the car framing.

Fig. 4 is a longitudinal vertical section taken on line 4—4 of Fig. 3, and showing the tank in position.

Fig. 5 is a fragmentary enlarged detail view partly in section of one end of the car.

Fig. 6 is a section on line 6—6 of Fig. 5.

Fig. 7 is a section on line 7—7 of Fig. 5.

Fig. 8 is a fragmentary detail view partly

in section illustrating the shock absorbing means at the center of the car.

Fig. 9 is a section on line 9—9 of Fig. 8.

Fig. 10 is a section on line 10—10 of Fig. 8.

Fig. 11 is a detail section on line 11—11 of Fig. 4.

As shown in the drawings:

The reference numeral 1, indicates as a whole the underframing of a car on which a tank 2, is mounted. Disposed upon and between the ends of center sills 3 and 4, extending longitudinally of the car frame, are integral casings, each denoted by the reference numeral 5. Said casings are rigidly secured to the respective center sills 3 and 4, by means of rivets or bolts which extend through the center sill and webs 5^a, integral with the bottom of the casing and fitting between the center sills. As shown also, each web 5^a, is provided with integral lugs 5^b, which, together with the rivets aforesaid, rigidly connect said casings with the sills, so that said casings in fact afford a part of the frame.

Mounted within each of said casings 5, are a plurality of groups of resilient friction plates 8, each comprising a plurality of substantially flat plates in frictional bearing face to face for their entire face areas, and varying in number in accordance with the shock absorbing capacity required. Arranged between successive groups are sliding spacing members 9—9^a, which space said groups apart alternately at their ends and at their centers, as shown in Fig. 7, and which permit curvature of the groups as a whole when sufficiently stressed by the abutment heads hereinafter described. Slidably mounted on the center sills adjacent each casing 5, is a metallic shoe 6, each provided centrally on its outer side with an abutment head 7, which extends into the adjacent casing 5, and bears against the outer group of spring friction plates. Said abutment heads, as shown in the drawings, are curved at their bearing faces and bear centrally on the corresponding spring groups, inasmuch as the spacing members between the first and the second spring groups separate the same at their ends. Each of said shoes 6, is shaped to receive and fit to the end of the tank 2, as shown in Fig. 5, extending sufficiently beneath the end thereof and upwardly therearound to adequately support the same and to afford a complementary seat for the end of the tank to distribute shock over a sufficiently large surface of the tank end.

An additional buffing gear is provided between the center sills intermediate the ends thereof. For this purpose a relatively short channel bar is secured in inverted position between the center sills near the middle of the car, and the flanges riveted to the webs

of the center sills sufficiently low thereon for the back of the channel to afford a horizontal floor or bottom 10, to support the gear. Near each end of said channel bar, and rigidly secured to the webs of the center sills, are fixed shoulders or abutments 11, against each pair of which a slideable transverse follower block 14, bears. Each of said follower blocks is convex at its inner face transversely the frame. Plates 13, are preferably arranged flat against the webs of the center sills between the abutments 11, and the follower blocks fit therebetween, as shown in Fig. 10. Fitting between the follower blocks 14, are a plurality of groups of spring friction plates 12, similar to those already described. Two groups are shown, which are spaced apart at their ends by the spacing member 15. Of course these groups may be of any number, and may consist of any number of plates in each group.

Secured upon the under side of the tank 2, substantially at the middle thereof, is a relatively large reinforcing plate 16, conforming to the curvature of the tank. A long I-beam 17, extending longitudinally of the tank and centrally between the center sills is secured at its middle to the reinforcing plate 16, on the under side of the tank, and also near the ends of the tank, by means of plates or brackets 18, which are riveted to the walls of the tank. The extreme ends of said I-beam fit into cored-out recesses or slots formed in the respective end shoes 6, and are riveted securely thereto between depending integral webs formed on said shoes. Thus any tendency for the tank to buckle upon its supports is eliminated and the application of a stress or load thereto at any point is transmitted and distributed longitudinally thereof through said I-beam and the respective members to which it is attached.

Rigidly secured to said I-beam 17, at each side the central buffing gear are abutment heads 19, which are spaced a distance apart to receive the outer faces of the respective follower blocks 14, of the center shock absorbing means therebetween, so that when the tank 2, is in a central position upon the car frame, said abutments fit closely against the follower blocks and with the groups of spring friction plates 12, but slightly stressed. Angle iron guides 20, are secured longitudinally on the inner surfaces of the center sills directly above the liner plates 13, and act to maintain said liner plates properly in position, as well as to prevent the resilient friction plates from buckling upwardly, guiding the same in their movement when the gear is stressed.

Of course any suitable retaining and guiding means for slidably supporting the tank upon the car may be provided, but for convenience I have only shown a simple

arrangement for the purpose, embracing longitudinally extending guides 21, forming a cradle in which the tank rests.

When a car is upon a curved track a buffering or draft stress transmitted thereto produces a transverse component or lateral displacing force, the inertia of the tank and its contents thus acting to displace the tank laterally from the car frame. To resist such a force and prevent displacement of the tank, I provide a number of straps or retaining bars 22, loosely extending circumferentially around the tank near the ends and at the middle portion thereof, but rigidly secured at their ends beneath the center sills of the car frame.

As illustrated in Figs. 1, 4, and 5, I have shown the car equipped with the customary draft and buffering gear 23, from which the drawbar 24, extends, having on its end a coupler head 25.

The operation is as follows:

The tank in its normal central position upon the car rests at its ends in the shoes 6, which are disposed such that the abutments 7, thereon are in bearing contact with the end groups of plates 8, in the respective cushioning devices at each end of the car frame, sufficiently stressing said gears normally to insure an immediate shock absorbing operation when an impact occurs. Similarly the central abutments 19, on the under side of the tank, fit tightly against the outer faces of the respective follower blocks 14, of the central shock absorbing means, which also normally stress said central gear as before described. In the event of a stress between the car frame and the tank, due to relative acceleration therebetween, as for example a severe buffering shock, the inertia of the tank will cause the abutment 7, of the sliding shoe 6, at one end to be forced inwardly against the resilient friction plates, and similarly at the central portion 45 of the car one of the abutments 19, will act to force one of the follower blocks 14, against the friction plates, which, of course, will be held by the opposite follower block 14, resting against the respective abutments 50 11. The friction plates 8 and 12, which are exactly similar in both the end and central absorbing devices, act to absorb the stress frictionally and by their resiliency, and because of the frictional contact between one 55 another, return to normal position slowly and without injurious recoil taking place.

It is to be understood, of course, that the usual draft and buffering gear of the car may absorb shock and stress for an inelastic load up to a considerable extent, but it is of course the object of my invention to employ the additional shock absorbing gears hereinbefore described to act in conjunction therewith and obviate the destructive effect 60 of greater stresses applied to the car frame.

There are a number of features of this invention which may be varied through a wide extent, as for instance there may be a plurality of buffering gears mounted intermediate the ends of the car frame, and if desired the respective shock absorbers at each end of the car may be so connected that both are brought into operation when an impact stress takes place between the car and the tank in a manner similar to the arrangement effected for the central shock absorber. However, I do not purpose limiting the patent granted otherwise than necessitated by the prior art.

I claim as my invention:

1. In a device of the class described a car frame, center sills, a tank movably mounted on the car frame, a longitudinal member secured thereto, plates thereon engaging under said center sills, a central butting head rigidly secured to each end of the tank and a shock absorbing mechanism at each end of the tank against which said butting head bears adapted to resist relative movement of the car and tank.

2. In a device of the class described a car frame, center sills, a tank movably mounted on the car frame, a longitudinal member secured thereto, plates thereon engaging under said center sills, a central butting head rigidly secured to each end of the tank, a shock absorbing mechanism at each end of the tank against which said butting head bears adapted to resist relative movement of the car and tank and a plurality of straps 100 extending loosely around the tank and rigidly secured at their ends to the center sills.

3. A tank car comprising a car frame, a tank mounted thereon to move relatively thereof, members rigidly secured to the bottom of the tank engaging the frame to prevent displacement of the tank, end members secured to the tank having integral abutting heads, a resilient plate shock absorbing mechanism mounted on the frame 110 at each end of the tank, an intermediate resilient plate shock absorbing mechanism and abutting heads rigidly secured to the tank and bearing against said shock absorbing mechanism.

4. A tank car comprising an underframe, a tank mounted thereon movable relatively thereof, a centrally disposed shock absorbing mechanism secured to the underframe at each end of the tank, a member secured 120 to each end of the tank adapted to coact with the respective shock absorbing mechanisms to prevent relative movement of the tank and underframe and to centralize the tank on the underframe.

5. A tank car comprising an underframe, a tank mounted thereon movable relatively thereof, a centrally disposed shock absorbing mechanism secured to the underframe at each end of the tank, a member secured 130

to each end of the tank adapted to coact with the respective shock absorbing mechanisms to prevent relative movement of the tank and underframe and to centralize the tank on the underframe, a centrally disposed shock absorbing mechanism, members rigidly secured to the tank engaging the same, bands loosely engaging around the tank having their lower ends rigidly secured to the underframe, and members secured to

the tank engaging on the underframe to hold the tank from vertical displacement.

In testimony whereof I have hereunto subscribed my name in the presence of two subscribing witnesses.

JAMES MILTON WAUGH.
